FIG.1

FIG.2

INVENTOR

Louis Steiner

UNITED STATES PATENT OFFICE

116,616

DESIGN FOR A VENDING MACHINE CASING OR THE LIKE

Louis Steiner, New York, N. Y., assignor to U-
Need-A-Pak Products Corporation, Brooklyn,
N. Y., a corporation of New York

Application June 8, 1939, Serial No. 85,400

Term of patent 3½ years

To all whom it may concern:

Be it known that I, Louis Steiner, a citizen of the United States and a resident of the city, county, and State of New York, have invented a new, original, and ornamental Design for a Vending Machine Casing or the like, of which the following is a specification, reference being made to the accompanying drawing, forming a part thereof.

In the drawing:

I claim:

The ornamental design for a vending machine casing or the like, as shown.
